UNITED STATES PATENT OFFICE.

CONRAD MÜLLER AND JOHN MAUSER, OF MORRISANIA, NEW YORK.

BARREL-REGISTER.

SPECIFICATION forming part of Letters Patent No. 268,926, dated December 12, 1882.

Application filed September 19, 1882. (No model.)

To all whom it may concern:

Be it known that we, CONRAD MÜLLER and JOHN MAUSER, of Morrisania, in the county of New York and State of New York, have 5 invented certain new and useful Improvements in Barrel-Registers, of which the following is a full, clear, and exact description.

Reference is to be had to the accompanying drawings, forming part of this specification, in 10 which similar letters of reference indicate corresponding parts in all the figures.

Figure 1 is a front elevation of our improvement, part being broken away. Fig. 2 is a 15 side elevation of the same. Fig. 3 is a sectional plan view of the same, taken through the line $x x$, Fig. 2.

The object of this invention is to provide 20 barrel-registers constructed in such a manner as to classify the barrels according to size and register the number of each size as the said barrels are being carried up an elevator or along a carrier.

The invention consists in a barrel-register 25 constructed with a weighted lever connected by gearing with a cylinder provided with teeth arranged in a spiral row to operate upon a series of parallel bars held forward by a sliding plate and spring and connected with the pawl-levers of a register. The sliding plate is locked 30 in position when holding the parallel bars in place, when pushed back by the last tooth of the cylinder, by a spring-pressed lever-pawl, which is tripped by an arm connected with the weighted lever as the said cylinder completes 35 its rearward movement, so that only one bar can be forced down at a time. To the parallel bars are attached adjustable stops to come in contact with the face of the cylinder and force the shoulders of the said bars off the 40 teeth of the cylinder promptly, as will be hereinafter fully described.

A represents the floor or other supports to which the standards or end frames, B, of the machine are secured.

45 To the upper forward parts of the standards B is journaled a shaft, C, with which is rigidly connected a lever, D.

To the lever D is attached a weight, E, of sufficient gravity to bring the said lever and 50 the various parts of the register to their nor-

mal position after the said lever has been raised. The outer end of the lever D, or of an arm, D', formed upon the said lever, projects into such a position as to be struck and raised by each barrel that passes along the elevator or carrier, 55 and is so formed as to slide easily upon the said barrel, as illustrated in Fig. 1.

The lever D can be secured directly to the shaft C; but we prefer to fit the inner end of the lever D into a socket, F, and secure it in 60 the said socket by a set-screw, G. The rear end of the socket F has a transverse hole formed through it to receive the shaft C, and is secured to the said shaft by a set-screw, H. With this construction, by loosening the set- 65 screw G the lever D can be detached and its shape can be changed, or it can be replaced with another lever of a different shape, as the direction in which the barrel is being carried by the elevator or carrier may require; and by 70 loosening the set-screw H the socket F, and with it the lever D, can be adjusted in any desired position upon the shaft C.

To the shaft C, near one end, is secured the hub of a segment, I, of a ratchet-wheel, the 75 teeth of which mesh into the teeth of a small gear-wheel, J, attached to the shaft K. The shaft K is journaled to the rear upper parts of the standards or frames B, and to it is attached a cylinder or drum, L, to the face of 80 which are attached as many lugs or teeth M as there are sizes of barrels to be registered. Each succeeding tooth M is placed a little in the rear of the preceding tooth M, so that the said teeth will stand in a spiral row. 85

At the rear side of the cylinder L are placed as many parallel upright bars N as there are teeth M on the said cylinder L, so that each bar N will be pushed back by its corresponding tooth, M, as the said tooth is raised by the 90 forward movement of the said cylinder. The bars N are drawn forward as each bar N is released from a tooth M by the spiral or other shaped spring O, one end of which is attached to the floor or support A, and its other end is 95 attached to the plate P, sliding upon the said support A, and kept in place by screws Q, passing through slots R in the said plate and screwing into the said support. The plate P has holes formed through its rear part to re- 100

ceive the lower ends of the bars N, so that all the said bars will be moved from and toward the cylinder L at the same time.

Upon the inner edge of each bar N is formed a shoulder, N', for the corresponding tooth M to strike against as the cylinder L is turned back, so that each bar N will be drawn downward by its tooth M by the backward movement of the said cylinder L.

10 To the forward edge of each bar N is attached a stop, S, which has a flange formed upon it to overlap the side of the bar N and receive the bolt T, by which the said stop is secured to the said bar. The bars N are slotted longitudinally to receive the bolts T, so that the stops S can be adjusted higher or lower, as may be required. With this construction, as the bars N approach the lower limit of their stroke the stops S come in contact with the 20 face of the cylinder L and are pushed back, withdrawing the shoulder N' of the bar N from the tooth M promptly and allowing the said bar to be raised to its normal position. The upper ends of the bars N are hinged to the 25 ends of the pawl-levers U of a register, V, which is constructed in the ordinary manner, except that the springs (not shown, they being arranged within the register-case) that raise the pawls and pawl-levers, after they are lowered in making a stroke, should be made strong enough to also raise the bars N, suspended from the said pawl-levers. The register V is made with as many index-fingers as there are bars N, and the said index-fingers can be arranged to move over the same dial or over 30 separate dials, as may be desired. We prefer to use one dial, as making the register more compact.

It will be noticed that were the pawl W, 40 hereinafter described, not provided, when the cylinder makes its rearward movement, after having been turned so far forward as to cause the third tooth M thereof to lift the shoulder N' of the third bar N, the first tooth of said 45 cylinder could not be prevented from engaging with the shoulder of its coincident bar during the continued rearward movement of the cylinder, when it is only desired that said third tooth shall engage with the shoulder of its bar, 50 the effect of which would be that a registration of two barrels would take place, instead of one, as should be the case, and thus make a false or untrue record. To prevent this incorrect registration, we pivot a lever-pawl, W, 55 to the floor or support A in such a position that its engaging end will be forced by a spring, X, attached to the support A, into a notch, Y, in the edge of the sliding plate P, when the said plate is slid back by the action of the third tooth upon the third bar N, the said third tooth being made longer than the others to cause it to move the said plate P a little farther than it is moved by the other teeth. The lever-pawl W, which is 60 brought into action with the sliding notched plate P when the third tooth of the cylinder L has been raised above the shoulder N' on

the coincident or third bar N, and which remains in engagement with the said plate after the said tooth has returned past the shoulder 70 of its bar upon the reverse movement of the cylinder, is tripped, when the first tooth has returned past the shoulder of its bar, by an arm, Z, attached to the shaft C, or to the hub of the gear-segment I, in such a position that it will 75 strike and trip the said lever-pawl at the proper time. By means of this construction only one bar N can be forced down at each rearward movement of the cylinder L.

In using the machine, as the different-sized 80 barrels are carried up an elevator or along a carrier the smallest barrels will raise the lever D high enough to cause the first tooth M of the cylinder L to rise with the forward turn thus imparted to the cylinder, and upon the 85 downward movement of the lever, which is caused by the escape of the barrel past it, the said tooth will be carried downward, the movement of its cylinder being thus reversed, and thus force down the first bar N. The next 90 larger barrels will raise the lever D so high as to cause the second tooth M of the cylinder L to rise above the shoulder N' of the second bar N, and be affected in like manner as the first tooth of the cylinder L, and cause 95 it to force down the second bar N; and the barrels of the third size will raise the lever D so high as to cause the third tooth M of the cylinder L to rise above the shoulder N' of the third bar N, and be similarly acted on as the 100 teeth of the two previous bars, and cause it to operate the third bar N, so that the barrels of each size will always lower their particular bar, and thus always operate their own register-index. 105

Having thus fully described our invention, we claim as new and desire to secure by Letters Patent—

1. A barrel-register constructed substantially as herein shown and described, and consisting of a weighted lever connected by a gearing with a cylinder provided with a spiral row of teeth to operate upon a series of bars held forward by a spring and a sliding plate and connected with the pawl-levers of a register, as set forth. 110

2. In a barrel-register, the combination, with the cylinder L, having spirally-arranged teeth M, of the gear-wheel J, gear-segment I, and weighted lever D, substantially as herein shown and described, whereby the said cylinder will be rocked for different distances by the movement of the said lever through correspondingly-different spaces, as set forth. 120

3. In a barrel-register, the combination, with the cylinder L, having a spirally-arranged row of teeth, M, and the pawl-levers U of a register, V, of a series of parallel upright bars, N, having shoulders N', substantially as herein shown and described, whereby the said bars will be 125 forced downward to operate the said lever-paws by the rearward movement of the said toothed cylinder, as set forth. 130

4. In a barrel-register, the combination,

with the bars N, connected with the lever-paws of a register, of the sliding plate P and the spring O, substantially as herein shown and described, whereby the said bars will be held forward and kept parallel, so as to always be in position to be operated upon by the teeth of the rocking cylinder, as set forth.

5. In a barrel-register, the combination, with the sliding plate P and the weighted lever D, of the lever-pawl W, the spring V, and the arm Z, substantially as herein shown and described, whereby the said sliding plate will be locked in place, holding the parallel suspended bars back from the tooth-cylinder, and will 10 be tripped by the said arm as the said cylinder is rotated.

15

der completes its rearward movement, as set forth.

6. In a barrel-register, the combination, with the parallel bars N, of the adjustable stops S, substantially as herein shown and described, whereby the shoulders of the said bars will be pushed off the teeth of the cylinder promptly by the contact of the said stops with the face of the cylinder, as set forth.
